(57) **CLAIM**

The ornamental design for a optical scope magnification throw lever, as shown and described.

DESCRIPTION

FIG. 1 is a pictorial view of the optical scope magnification throw lever shown in context as used on an optical scope; FIG. 2 is a side plan view of the optical scope magnification throw lever shown in FIG. 1, all side views being identical; FIG. 3 is a top view; and, FIG. 4 is a bottom view.

The dashed lines form no part of the claimed invention in this application and are instead included to show environment of the design.
